UNITED STATES PATENT OFFICE.

KARL LIDBECK AND VERNER BRYNGELSON, OF NIAGARA, WISCONSIN.

SWINGING-DOOR CHECK.

Application filed June 10, 1925. Serial No. 36,255.

To all whom it may concern:

Be it known that we, KARL LIDBECK and VERNER BRYNGELSON, citizens of the United States, residing at Niagara, in the county of

5 Marinette and State of Wisconsin, have invented new and useful Improvements in Swinging-Door Checks, of which the following is a specification.

This invention relates to a door check, the 10 general object of the invention being to provide a simple device for checking the swinging movement of a door and one which will stand the strain imparted to it by a door which is in extensive use.

15 Another object of the invention is to provide means whereby the check can be easily and quickly applied for use on a door which swings both ways.

This invention also consists in certain 20 other features of construction and in the combination and arrangement of the several parts, to be hereinafter fully described, illustrated in the accompanying drawings and specifically pointed out in the appended 25 claims.

In describing the invention in detail, reference will be had to the accompanying drawings wherein like characters denote like or corresponding parts throughout the several 30 views, and in which:

Figure 1 is an elevation showing the invention in use.

Figure 2 is a section on line 2—2 of Figure 1.

35 Figure 3 is a top plan view showing the door open.

Figure 4 is a section on line 4—4 of Figure 2.

40 Figure 5 is a detail sectional view through the lower portion of the hinged part of the door.

In these views 1 indicates a door frame and 2 indicates the door, this door being provided with a hinge arrangement which 45 will permit it to be swung in either direction. The check for the door comprises an L-shaped bracket 3 which is fastened to the door frame, an arm 4 which is pivoted to the outer end of the bracket and which has a flat portion 4' adjacent its outer end for engaging a part of the door and a spring 5 which connects the arm with the bracket and tends to hold the arm with a shoulder thereon against a shoulder on the bracket, these 55 shoulders limiting the inward movement of the arm. In this position the arm will be

resting against a face of the door with the door in closed position. In order to prevent wear on the door, a plate 6 is fastened thereto and the part 4' on the arm 4 engages 60 said plate.

It will thus be seen that when the door is pushed open the part 4' will slide on the plate 6 and the movement of the arm on its pivot will stretch the spring 5 and thus the movement of the door is resisted by the spring. In this way the pressure of the arm on the door will check the opening movement of the door and will also return the door to closed position after the force which 70 opens the door is removed therefrom.

When the device is used on a door which swings in both directions, a bracket 7 is fastened to the arm 4 and a spring 8 connects said bracket to a bracket 9 on the door so 75 that when the door is pushed away from the device, this spring 8 will be stretched and will act to return the door to closed position.

As will be seen, the device is very simple, contains few parts and the parts are of considerable strength so that the device can be used on a door which is used a great number of times. It can be easily converted into a check for a door opening in either direction.

The drawings show the door as provided with a novel form of hinge which consists of a rod-like member 10 connected with the rear edge of the door and having its upper end engaging a circular bearing hole 11 formed in a plate 12 fastened to the top of the door frame and its lower end engaging a bearing hole 13 formed in a plate 14 fastened to the door sill above a plate 15 which carries a ball 16 upon which the lower end 95 of the member 10 rests. This provides a strong hinge which is supported upon a ball bearing with its end rotatably mounted in plates in the door frame.

It is thought from the foregoing description that the advantages and novel features of the invention will be readily apparent.

We desire it to be understood that we may make changes in the construction and in the combination and arrangement of the several 105 parts, provided that such changes fall within the scope of the appended claims.

What I claim is:—

1. A door check comprising an L-shaped bracket adapted to be connected with a door 110 frame, an arm pivoted to the outer end of the bracket and having its outer end adapted to

engage a door, a spring connecting the arm with the bracket, a projection on the arm and a spring connected with the outer end of the projection and adapted to be connected with a door.

2. In combination with a barrier and its frame, an angle-shaped bracket connected with the frame, a curved arm pivoted to the outer end of the bracket and having a flat part on its outer end for engaging the bar-

rier, a spring connecting the outer part of the arm with the bracket, an extension on the arm, a spring connecting the outer end of the extension with the barrier, and a wear plate on the barrier and engaged by the flat part ¹⁵ of the arm.

In testimony whereof we affix our signatures.

KARL LIDBECK.
VERNER BRYNGELSON.
